UNITED STATES PATENT OFFICE.

ROBERT S. BUSBY, OF JACKSONVILLE, FLORIDA.

HAIRPIN.

Application filed October 18, 1920. Serial No. 417,654.

To all whom it may concern:

Be it known that I, ROBERT S. BUSBY, a citizen of the United States, residing at Jacksonville, in the county of Duval and State of Florida, have invented certain new and useful Improvements in Hairpins, of which the following is a specification.

My present invention relates to hairpins and more particularly to such embodying the usual pair of projections from the head and in addition a pair of auxiliary projections which assist in maintaining the pin in the desired position.

The principal objects of the invention are to provide hair pins embodying auxiliary projections which are so shaped and positioned relative to longer main projections of the head of the pin that the hair adjacent the head of the pin, when in place, is divided into three strands where it passes between the projections, one of which is greater than the other and positioned next adjacent to the head of the pin expanded so to speak, and concealing the head of the pin and the smaller strands similarly expanded remote from the head of the pin to conceal the projections of the head; to provide hair pins embodying auxiliary projections which are so arranged as to provide a flat compact article of manufacture, a large number of which may be packed or bundled compactly; and to provide auxiliary projections of wire of smaller size than the main projections, so as to yield more readily when inserted into the hair yet of sufficient size to serve their function as an aid in retaining the pin in the desired position.

Other objects and advantages of the invention will appear in the following detailed description, taken in connection with the accompanying drawings, forming a part of this specification, and in which drawings:

Figure 1 is a front view of a hair pin embodying my invention.

Fig. 2 is a sectional view on the line 2—2 of Fig. 1.

In the drawings 3 designates generally the head of the pin, 4 the main projections from the head and 5 auxiliary projections all extending from the head in substantially the same direction, and in the same plane.

It is preferred to provide the projections 4 with waves 6 intermediate their ends, said waves being in substantially the same plane as the projections 5.

The head 3 may be rounded, as is usual

and integral with the projections 4, and the auxiliary projections may be integral with head 3, or welded, soldered or otherwise secured thereto to lie between the projections 4. These projections 5 are of relatively smaller cross section than the projections 4, that is they may be formed of wire of less gage than the wire from which projections 4 may be formed thereby more readily yielding as the pin is forced or trained into the hair.

In order to divide the strand of hair, which is initially caught between the projections 4, into three strands, the central one of which is larger than the outer two, the relatively short projections 5 are disposed between the projections 4, preferably at relatively straight portions 7 thereof. These projections 5 lead from the head 3 in converging relation as at 8; then bulged inwardly toward the longitudinal axis of the pin as at 9, the crowns of the bulges confronting one another and providing a constricted passage way 10 for the hair; then bulged outwardly toward the projections 4, as at 11 providing constricted passage ways 12 for strands of hair; and finally terminating in converting end portions 13 separated as at 14, a greater distance than the constricted portion 10 between the confronting crowns of bulges 9.

It will thus be seen that, as the pin is forced or trained into the hair, the strand caught between the projections 4 will be divided into three strands by the projections 5. This division is such that the central strand of the three is greater than the outer two, the hairs of the central strand passing through constricted portion 10 and separating or expanding, so to speak, between the converging portions 8, closely adjacent the head 3, and the hairs of the outer strands passing through constricted portion 12 and separating or expanding between the portions 8 and 9 of the auxiliary projections 5 and portions 7 of projections 4. The looping or natural waving of the hair thus permitted to separate or in other words expanded strands will effectively conceal the head of the pin and adjacent portions of the projections, for any inherent tendency of the hair to straighten out after the pin has been pushed into the hair will be resisted by the constricted passage ways 10 and 12.

By reference to Fig. 2 of the drawing it will be observed that, disposing all of the

bends or waves of the projections of projections 4 and 5 in substantially the same plane the pins may be compactly packed one next adjacent the other.

5 I claim:

1. A hair pin comprising a head, a pair of main projections in spaced apart relation with comparatively straight portions leading therefrom and a pair of auxiliary pro-

10 jections disposed between the said straight portions of said main projections, said auxiliary projections leading from said head with portions next adjacent thereto in con-

15 verging relation for a part of their length, then bulged inwardly toward the longitudinal axis of the pin with the crowns of the bulges confronting one another and providing

20 a constricted passage way, then bulged outwardly toward the said straight portions of said main projections providing constricted passage ways therebetween, and having end portions in converging spaced relation.

2. A hair pin comprising a head, a pair of main projections in spaced apart relation with comparatively straight portions leading therefrom and a pair of auxiliary pro-

25 jections disposed between the said straight portions of said main projections, said auxiliary projections leading from said head with portions next adjacent thereto in con-

30 verging relation for a part of their length, then bulged inwardly toward the longitudinal axis of the pin with the crowns of the

bulges confronting one another and providing a constricted passageway, then bulged 35 outwardly toward the said straight portions of said main projections providing constricted passage ways therebetween, and having end portions in converging spaced relation, the space between the ends of said auxiliary 40 projections being greater than the space between the confronting crowns of said first mentioned bulges.

3. A hair pin comprising a head, a pair of main projections in spaced apart relation 45 with comparatively straight portions leading therefrom and a pair of auxiliary pro-

jections disposed between the said straight portions of said main projections, said aux- 50 illary projections leading from said head with portions next adjacent thereto in con-

verging relation for a part of their length, then bulged inwardly toward the longitudi- 55 nal axis of the pin with the crowns of the bulges confronting one another and providing

a constricted passage way, then bulged outwardly toward the said straight portions of said main projections providing constricted passage ways therebetween, and having end portions in converging spaced relation, 60 said auxiliary projections of relatively smaller cross sectional area than said main projections and lying wholly between the parallel planes of the faces of the main pro- 65 jections.

ROBERT S. BUSBY.
